UNITED STATES PATENT OFFICE.

FREDERICK A. PHELPS, OF NEWARK, NEW JERSEY.

DESIGN FOR A VEHICLE-MOTOR CASING.

SPECIFICATION forming part of Design No. 32,408, dated March 27, 1900.

Application filed December 16, 1899. Serial No. 740,599. Term of patent 31 years.

To all whom it may concern:

Be it known that I, FREDERICK A. PHELPS, a citizen of the United States, residing at Newark, in the county of Essex and State of New Jersey, have invented and produced a new and original Design for a Vehicle-Motor Casing, of which the following is a specification, reference being had to the accompanying drawing, forming part thereof.

10 In the drawing is shown a perspective view of my casing, one view being deemed sufficient to fully illustrate the design.

The leading features of my design consist in the casing for a vehicle-motor shown in 15 the drawing, the front portion of which is oval or oblong in cross-section and is indicated by the letter A and surrounds a water-lined jacket for the explosion-chamber and

the working part of the cylinder-barrels; the rear portion B, forming the crank-chamber, 20 cylindrical in shape; the two round barrel portions A' A', connecting the front and rear portions, forming extended parts of the cylinders and acting as guides for the pistons; the supports a and b, integral with the casing, 25 and the head of the casing, having the bearings K K K.

I claim—

The design for a vehicle-motor casing, as herein shown and described. 30

In testimony whereof I have affixed my signature in presence of two witnesses.

FREDERICK A. PHELPS.

Witnesses:

JOHN F. KERR,
FLOYD M. WILLIAMS.
